UNITED STATES PATENT OFFICE

1,936,310

LAUNDRY TRAY

Giuseppe Rodota, San Francisco, Calif.

Application November 7, 1932. Serial No. 641,631

3 Claims. (Cl. 68—31)

My invention relates to improvements in laundry trays, laundry tubs, and the like, and particularly to a laundry tray of the type having a built-in scrubbing board, and especially constructed and formed to facilitate the efficient and convenient use of such scrubbing board.

It is also an important object of my invention to provide in a device of the character described, a removable and replaceable scrubbing board, 10 which does not in any way detract from the capacity of the device, but which enables scrubbing operations usually carried on with a separate washing board, to be carried out without encumbrance by such separate washing board.

15 It is also an important object of my invention to provide in a device of the character described, a removable washing board which is substantially flush with one surface of the device, which surface is disposed at the correct angle for facilitating convenient and efficient use of the washing board, which washing board in no way encumbers the interior of the device, and does not add to the bulk of the device.

20 It is also an important object of my invention to provide a washing tray or tub of the character described which includes all of the features and advantages stated above, in an inexpensive yet thoroughly workmanlike and attractive form, and which is simple and adapted to quantity production in manufacture.

25 Other objects and advantages of my invention will be apparent from a reading of the following description in connection with the drawing, wherein for purposes of illustration I have shown 30 a preferred embodiment of my invention.

35 In the drawing:—

Figure 1 is a top view of the embodiment.

Figure 2 is a longitudinal vertical sectional view through Figure 1.

40 Referring in detail to the drawing, wherein like numerals refer to like parts throughout the same, the numeral 5 refers generally to a suitable form of laundry tray or wash tub, on the interior surface of one wall of which is constructed the removable washing board generally designated 6.

45 The tray or tub 5 may assume a generally conventional form as to dimensions and contour. In such a structure I provide an unusually thick front wall 7 which may be of any suitable material such as concrete. It will be seen that the wall 7 has its outer surface 8 disposed at a convenient angle to the perpendicular, while its interior wall 9 is disposed at a greater angle to the perpendicular, so that the wall 7 tapers upwardly, and forms a strong and stabler support

to bear the extra stress to be placed thereon while the device of the invention is in use, and to take care of the generally rectangular depression or recess 10 which is formed in the interior surface 9 thereof.

50 As seen in Figure 1, the recess 10 may be elongated transversely of the tray and extend from a point slightly below the upper edge of the wall 7 to a point at a greater distance from the lower end of the interior wall 9. This is to give a proper position to the recess 10, enabling the washboard structure to be placed therein to be as completely accessible as possible, and to be of the greatest size practical.

55 At several points, particularly near the side edges of the depression 10, openings 11 are made into the wall 7 from the bottom of the depression 10, and in which are embedded brass or other suitable metallic sockets 12 having threaded openings therein to receive screws 4 attaching and holding in place the washboard structure generally designated 13.

60 Lining the side walls of the depression 10 is a zinc or other suitable soft material rim 14 which is adapted to cause a snug engagement of the washboard 13 in the depression, so as to prevent the building up of deposits of soap and other washing materials, and to prevent corrosion and other deterioration. This rim also prevents chipping of the edges of the brittle material of the tray surrounding the depression 10 when removing and replacing the removable washboard 13 and similarly protects the edges of the washboard. The rim 14 is secured in place by embedding portions thereof in the material of the tray in some 70 conventional manner such as that shown in U. S. Patent No. 1,735,600 issued to Grogan on May 12, 1925.

75 The washboard 13 may be constructed of glass, or of other suitable material and has transverse corrugations 15 of any desired type formed on one side thereof. A glass washboard 13 forms a very desirable construction, though a non-rusting and non-corroding metal form performs very adequately. The washboard is made of a size to 80 snugly fit within the rim 14 and seat in the depression 10 so that its corrugations 15 are approximately flush with the interior surface 9 of the wall 7. Screws 16 are placed through openings in the washboard for threading into the sockets 12 for securing the washboard in place. The openings through which the screws pass through the washboard 13 will be countersunk so as to 85 permit positioning the heads of the screws below the corrugations. It will be obvious that owing 90

to the provision of the rim 14 which prevents in the manner described, sticking of the washboard in the depression, the washboard may be easily removed and replaced when desired or necessary 5 simply by loosening the screws 16 when removing the same and replacing the screws and tightening them when replacing the washboard. The embedded sockets 11 enable securely and rigidly mounting the washboard without straining or mutilating the wall 7, which wall 7 has also been specially prepared and formed to accommodate the extra strain and weight imposed thereon in the use of the device of the invention.

It will be observed that because of the excellence of the arrangement of the depression 10, of the rim 14, and of the angularity of the wall 9, the washboard 13 is securely held in position and is capable of resisting the various strains imposed thereon in scrubbing and washing operations, with 10 the simple and relatively small and easily manipulated fastening means described.

Though I have shown and described herein a preferred embodiment of the invention, it is to be definitely understood that I do not desire to limit the application of the invention thereto, and any change or changes may be made in material and structure and arrangement of parts, within the spirit of the invention and the scope of the subjoined claims.

30 What is claimed is:—

1. In a cement washing tray having a thickened inclined front wall, the interior surface of said wall having a depression therein, a removable washboard of frangible material disposed in said depression flush with the surface of the interior wall, the bottom of said depression having sockets, threaded receptors embedded in the sockets, screws passed through holes provided in the washboard and threaded into the threaded receptors, and a soft metal rim disposed between the side walls of the depression and the side edges of the washboard when the same is in the depression for snugly filling the space between the washboard and the side walls of the depression to make a

snug fit and render the washboard easily removable and replaceable, and protect the edges of the depression and of the washboard against chipping.

2. In a concrete washtray having an inclined front wall provided with a washboard receiving depression on its inner surface; a washboard of frangible material disposed in the depression and flush with the surface of the inner surface, the edges of the washboard being slightly spaced from the side walls of the depression, a protective packing member located in the depression between the edges of the washboard and the side walls of the depression for preventing chipping of the edges of the depression and the washboard and for providing a snug and protective engagement of the washboard in the depression and provide for easy removal and replacement of the washboard and prevent accumulation of matter in the depression and between the edges of the washboard and the side walls of the depression.

3. In a concrete washtray having an inclined front wall provided with a washboard receiving depression on its inner surface; a washboard of frangible material disposed in the depression and flush with the surface of the inner surface, the edges of the washboard being slightly spaced from the side walls of the depression, a protective packing member located in the depression between the edges of the washboard and the side walls of the depression for preventing chipping of the edges of the depression and the washboard and for providing a snug and protective engagement of the washboard in the depression and provide for easy removal and replacement of the washboard and prevent accumulation of matter in the depression and between the edges of the washboard and the side walls of the depression.

GIUSEPPE RODOTA.
